DOOR-CHECK.

1,239,510.

Specification of Letters Patent. Patented Sept. 11, 1917.

Application filed April 26, 1915. Serial No. 24,140.

To all whom it may concern:

Be it known that I, RONALD E. J. NORDQUIST, a subject of the King of Sweden, residing at Oak Park, in the county of Cook 5 and State of Illinois, have invented a certain new and useful Improvement in Door-Checks, of which the following is a specification.

This invention relates to door checks and 10 is an improvement upon the invisible door checks shown in several prior patents. The object of the invention is to provide a novel form of valve device controlling the opening or passageway within the check through 15 which liquid flows in the usual manner, to control the movement of the door, this valve device being so arranged that while a normal speed of door movement is maintained under ordinary conditions the valve may, 20 under extreme pressure upon the door, yield to allow a more rapid movement of the door and thus avoid injury to the checking device; this in combination with automatic 25 means for varying the normal opening of the valve and with means operable from outside the device for adjusting said opening.

The invention consists in a device capable of carrying out the foregoing objects which can be very easily and cheaply made and in- 30 stalled, which is satisfactory in operation and is not readily liable to get out of order. The invention further consists in the features and details of construction hereafter more fully set forth in the specification and 35 claims.

In the drawings,

Figure 1 is a sectional view of mechanism illustrating this invention applied to a door, the door being shown in closed position.

Fig. 2 is an enlarged detail view of the 40 right hand portion of Fig. 1; the inner end of the check showing the parts in the position which they assume when the door is open.

Fig. 3 is a view corresponding to Fig. 2, showing the parts in intermediate position between that of Figs. 1 and 2.

Fig. 4 is a sectional detail view on the line 4—4, of Fig. 2, and

Fig. 5 is an end view on the line 5—5, of Fig. 3.

As in all door checks of this class, the mechanism includes a pair of plates 10 and 12, placed opposite to each other, the former being inserted in the door jamb 14, the lat-

ter in the door 16, and the plate 12 carrying the door check case consisting broadly of the housing 18, tubular member 20 and closing cap 22, of ordinary construction. Similarly, as in the old art, the check has a piston 60 rod 24 slidable through a suitable packing 26 in the left hand end of the check, the left end of this rod 24 being connected by a link 28 to a post 30 on plate 10, the result being that as the door 16 is swung on its 65 hinges forward and backward from closed to open position, the rod 24 is reciprocated backward and forward within the check casing between the positions of Figs. 1 and 3.

The packing 26 is spaced from the piston 70 rod 24, and packing glands 26^a and 26^b are secured in each end of the packing 26 around the piston rod, thereby forming a chamber 26^c around the piston rod between the said glands, so that the oil which may seep 75 through in the course of time, instead of escaping into the outside atmosphere, where it will gum and harden, is caught in the said chamber. Such oil as does pass into the chamber, moreover, serves to lubricate the 80 piston rod, and is likely to pass out of the chamber and back into the casing of the check. This packing is, therefore, superior to anything in the prior art and tends to keep the check in working order for a much 85 longer period of time than has been possible with any construction heretofore known.

In the device illustrating this invention in its preferred form here shown, an internal head 32 is rigidly attached to the inner right 90 hand end of the casing 20 and parts 18 and 32 are connected together within the casing by two oppositely placed tubular members 34 and 36. Inclosing these two tubular members, just mentioned, are coiled springs 38 95 and 40 bearing at one end against member 18 and at the other end against a flange or cross-head 42 carried on the end of an inner cylinder 44 screw threaded onto the right hand end of piston rod 24 at 46, the result being 100 that, under normal conditions, the springs 38 and 40 press the cross-head 42 and consequently the cylinder 44 and rod 24 to the right, as viewed in the figures, until all of the parts reach the position of Fig. 1 and the 105 door is closed; in other words, springs 38 and 40 are the door control springs.

Through the left hand end or head of cylinder 44 is a port or passageway 48—50 controlled by a ball valve 52. Rigidly attached 110

to the internal head 32, heretofore referred to, by any suitable means, such for instance as screw threads 56, is a cylinder 58 concentric with cylinder 44 but loose enough inside of movable cylinder 44 so that the latter 5 may freely slide over this cylinder 58. About the left hand end or head of this inner cylinder 58 is a packing device 60 of any suitable construction, while through the center 10 of this head is a port or passageway 62. Cylinder 58 is provided with a discharge port 66 and cylinder 44 is provided with a similar port 68, permitting oil or other working fluid which has passed from left to right through 15 passageway 62, in the manner hereafter described, to return into the main interior chamber of the check case, ready to be used again in the manner well known in the art.

The outer or right hand end of head 32 is 20 provided with a suitably formed recess 70 within which is located a lever 72 pivoted at 74. Through this lever 72 near pivot 74 is inserted a valve rod 76 provided at its right hand end with a head 78 which bears against 25 the lever 72 and at its opposite end with a point 80 entering and moving within cylinder 58 and adapted to control the right hand end of passageway 62, heretofore described. On this valve rod 76 near its left 30 hand end is a shoulder 82 and between this shoulder and the adjacent member 32 and within the cylinder 58 is placed a coiled spring 84 which, in the obvious manner, tends to force valve rod 76 to the left, as 35 viewed in the figure, and consequently force the point 80 of said rod to seat itself in, and close the end of passageway 62.

Pivoted at 90 in the head 32 is a lever 92 having a hooked end 94 engaging and bearing 40 against the lower end of lever 72, and an opposite end carrying a cam 96 lying inside of tube 36, heretofore referred to, adapted to be engaged by a cam lug 98 mounted upon cross-head 42 and traveling backward and 45 forward along the bottom edge of tube 36, the cam lug 98 entering said tube through a suitably formed slot 100 therein. This cam 96 and cam lug 98 are so arranged, shaped and located that when the parts are in the 50 positions of Figs. 1 and 2, the lever 92 is not materially affected by the cam but that when the parts are in the position shown in Fig. 3, member 98 engages cam 96 and elevates it as shown in Fig. 3, thus rotating lever 92 in a 55 clockwise direction about pivot 90 and thus correspondingly rotating lever 72 about pivot 74. This movement of lever 72 obviously moves head 78 on valve rod 76 to the right thereby withdrawing point 80 of rod 60 76 from its seat thus increasing the amount of liquid which can flow through passageway 62.

Extending through the inside of tube 34, heretofore described, is a rod 110 carrying 65 on its left hand end a head 112 provided with

a screw driver notch 114 adapted to be engaged by a screw driver in the hands of an operator standing at the edge of the door. Other means for adjustably rotating this rod 110 may be provided without departing from 70 this invention. Means, such as the ring 116, is provided for preventing longitudinal movement of rod 110 without interfering with its rotation. Suitable packing devices 120 may also be provided for this rod 110 75 when and if desired.

The right hand end 122 of rod 110 is made non-circular in cross-section and it enters a block 124 screw threaded at 126 into head 32. The result of the foregoing construction 80 is that an operator, by turning head 112 of rod 110, may turn block 124 and cause it to move in and out of member 32 on screw threads 126.

Screw threaded into block 124 is a bolt 130 85 whose non-circular head 134 lies in the U-shaped recess formed in the upper end of lever 72, the fit of the parts being such that the lever 72 may freely rock on pivot 74 so long as the bolt head 134 is in its normal position shown in Fig. 5, but the screw or bolt 130 can not be rotated; in other words, this means is provided for holding bolt 130 stationary while block 124 is rotated and consequently the relationship longitudinally 90 of the bolt and block is regulated. Extending transversely of the bolt 130 are horizontal arms 138 against which the lever 72 bears.

From the foregoing, it is seen that the 100 arms 138 on bolt 130 form a stop limiting the movement of the upper end of lever 72 to the left and that the position of this stop is adjustable by the operator outside the door who applies a screw driver to the notch 105 114 in head 112 on rod 110 and rotates it in the direction desired to vary the relative positions as may be needed of the block 124 and the bolt 130.

In the operation of the device, the entire 110 interior of the exterior case 18-20-22 is substantially filled with checking liquid, usually oil. Assuming the parts are in the position of Fig. 1 and the operator presses against the outside of the door 16 to open it. 115 This, in the obvious manner, well known in the art, pulls rod 24 and cylinder 44 to the left, as viewed in Fig. 1 until the parts, after passing the position of Fig. 3 reach that of Fig. 2, in so doing compressing springs 120 38 and 40. During this movement, the oil or other checking liquid freely flows through passageway 48, past ball 52 and through passageway 50 into the interior chamber 144 of cylinder 44, closed by the left hand end 125 or head of cylinder 58 within which passageway 62, heretofore referred to, is located.

When, now, the operator releases the door, and it begins to close, either through the compressed springs 38 and 40, or through 130

the agency of an external spring forming no part of this invention or through pressure by the operator himself, this closing pressure tends to force cylinder 44 back over cylinder

- 5 58, but this movement can only take place as rapidly as the liquid in space 144 in cylinder 44 can flow through passageway 62 and its right hand end controlled by point 80 of valve rod 76. When the parts are in 10 the position shown in Figs. 1 and 2, lever 72 is in such a position that valve rod 76 is pressed by spring 84 as far as it will go to the left with the result that the discharge opening 62—80 is as small as it is desired to be made, and the door will, therefore, in this 15 position of the parts close as slowly as the operator of the device intended it should close, except as the ultimate position of lever 72 is regulated by the turning of rod 110 20 and consequently bolt 130 in the manner heretofore described, to adjust the position of stop 138. In this position of the parts the door will close slowly under the action of the check for the reason that the spring 25 84 is of sufficient strength to, under normal conditions, force the point 80 of rod 76 as far as it will go toward the discharge opening of passageway 62. This spring 84 is, however, sufficiently weak so that when an 30 excessive pressure is applied to the door itself thereby creating an excessive pressure in chamber 144, this latter excessive pressure will be applied to the stream of liquid going out of passageway 62 with the result that 35 valve rod 76 is forced to the right and the opening 62—80 is enlarged to its maximum.

When member 98, heretofore referred to, reaches the position of Fig. 3, it, in engagement with cam 96, rotates lever 92 in a clockwise direction from that of Fig. 2 and correspondingly moves lever 72 with the result that head 78 on valve rod 76 is moved to the right. The movement of this rod under spring 84 to the left is correspondingly limited by the position of lever 72, and this lever, therefore, prevents point 80 of rod 76 entering the end of passage 62 as closely as is shown in Figs. 1 and 2 with the result that the heretofore described normal opening of passage 62—80 is correspondingly increased. In practice, the cam 45 96 is so shaped and the member 98 is so located that this enlarged opening is maintained during the portion of the swing of 50 the door when it is most desirable that it close rapidly.

It will be seen from the foregoing that by this device the normal discharge area of the passageway controlling the checking fluid 55 is automatically varied in size as the door moves; that the valve is automatically releasable when an excessive pressure is exerted upon the door, and that the valve is adjustable at all times from outside the device.

It will, of course, be understood by those skilled in the art that the checking liquid, after passing to the right through passageway 62 and past valve point 80, return via ports 66 and 68 to the main chamber of the 70 check.

By adjusting rod 110 so that valve 62—80 completely closes, the door may be secured by the check in any selected open position.

Having thus described my invention, what 75 I claim as new and desire to secure by Letters Patent, is:—

1. In a door check and closer, the combination of a casing, a fluid discharge port or passageway in said casing, a valve controlling the said port, means tending to move the valve toward said port, a pivotally-mounted lever having an operative connection with said valve, and a second lever pivotally mounted in said casing one end of 85 which is operatively engaged with the first-named lever while its other end is free.

2. In a door check and closer, the combination of a casing, a fluid discharge port or passageway in said casing, a valve controlling said port, means tending to move the valve toward said port, a pivotally-mounted lever having an operative connection with said valve, a second lever pivotally mounted in said casing one end of 90 95 which is operatively engaged with the first-named lever while its other end is free, a cam on the free arm of the second-named lever, and means having coöperative engagement with said cam for operating said lever. 100

3. In a door check and closer, the combination of a casing, a fluid discharge port in said casing, a valve for said port, means tending to move the valve toward said port, a pivotally-mounted lever having operative 105 connection with said valve, a slot in one end of said lever, a second pivotally-mounted lever the short arm of which passes through said slot and has operating connection with the first-named lever, a cam on the long arm 110 of said second-named lever, and means having coöperative engagement with said cam for operating said levers.

4. In a door check and closer, the combination of a casing, a fluid discharge port 115 in said casing, a valve for said port, means tending to move said valve toward said port, a pivotally-mounted lever having operative connection with said valve, an abutment for one end of said lever for determining the 120 movement of said lever, means extending from said abutment through the casing and to the exterior of the casing whereby the abutment may be adjusted from the exterior of the casing, a lever pivotally mounted in 125 the casing with its short arm having operative engagement with the first-named lever, a cam on the long arm of the second-named lever, and means coöperative with said cam to operate the first-named lever. 130

4

5. In a door check and closer, the combination, with the fluid-controlling valve within a casing and a lever to control said valve, of an abutment to limit the movement 5 of said lever, said abutment comprising a screw-threaded block, an abutment screw-threaded in said block and adapted to be engaged by said lever and when so engaged is held against rotation, a rod non-rotatably 10 connected with said block and extending to the exterior of the casing whereby it may be rotated and in turn rotate the block and

thereby regulate the distance said abutment projects from said block and thus regulate the extent of movement of said lever, said 15 adjustment being made exterior of the door in which the check and closer is positioned.

In witness whereof, I have hereunto subscribed my name in the presence of two witnesses:

RONALD E. J. NORDQUIST.
